UNITED STATES PATENT OFFICE.

WILLIAM S. WITTEN, OF CHICAGO, ILLINOIS.

HAND-CART.

1,043,993.

Specification of Letters Patent. Patented Nov. 12, 1912.

Application filed April 24, 1909, Serial No. 491,937. Renewed July 22, 1912. Serial No. 710,976.

To all whom it may concern:

Be it known that I, WILLIAM S. WITTEN, a citizen of the United States, residing at Chicago, in the county of Cook and State 5 of Illinois, have invented certain new and useful Improvements in Hand-Carts, of which the following is a specification, reference being had to the accompanying drawings.

10 My invention relates to hand-carts, and has for its object to provide a new and improved hand-cart suitable for use in the transportation of dirt and other materials, and which may be easily dumped when de- 15 sired to discharge its load. I accomplish this object as illustrated in the drawings and as hereinafter described.

What I regard as new is set forth in the claims.

20 In the drawings,—Figure 1 is a side elevation of my improved cart, showing in dotted lines the dumping position of the box or bed, one wheel being removed; Fig. 2 is an enlarged detail, being a partial sectional view illustrating one of the front corners of the box; Fig. 3 is an enlarged detail, being a partial vertical section showing the rear end of the box; Fig. 4 is a plan view; and Fig. 5 is a rear elevation.

25 Referring to the drawings,—6—7 indicate the upper and lower members, and 8—9 the front and rear members of the side-frames of the cart, said members being preferably made of gas-pipe suitably joined together. The upper and lower members 6—7 are parallel with each other and are connected at their rear ends by the rear member 9, which is vertically disposed. At their 30 forward ends they are connected by the member 8 which is inclined forward and upward, as shown in Fig. 1. The side frames are connected at their forward ends by a cross-member 10, also of gas-pipe, as shown in Fig. 4, said member being in sub- 35 stantially the same plane as the upper members 6 of the side frames,—it being understood that the two side frames are alike.

40 11—12 indicate upper and lower members, respectively, which connect the rear ends of the side frames, as shown in Fig. 5, said members 11—12 being also of gas-pipe.

45 13 indicates a rear support or standard, which is formed of gas-pipe bent to V-shape, as shown in Fig. 5, its ends being uppermost and connected with the vertical mem-

bers 9 of the side frames. If desired, the members 9 and 13 may be formed integral with each other or they may be connected in any suitable way. I thus form a frame rectangular in plan view, which surrounds 50 the bed or box 14 of the cart, as best shown in Fig. 4.

55 15—16 indicate supporting-wheels mounted on the axle 17 which is suitably supported by or connected to the lower members 7 of the side frames, as shown in Figs. 1 and 4. The axle 17 is placed at about the longitudinal center of the side frames, and the bed 14 is pivotally mounted thereon, so that it turns about the axle 17 as an axis, as 60 indicated by dotted lines in Fig. 1. The bed 14 is a box rectangular in shape and open at its front end.

65 18 indicates the sides of the box, which, as shown in Figs. 1 and 2, are curved in the 70 arc of a circle of which the axle 17 is the center.

75 19 indicates a latch, which is pivoted at its upper end on a pivot 20 secured to the rear end of the box 14 and extends downward from the pivot adjacent to the rear 80 face of the box in the manner shown in Fig. 1. Said latch has a hook 21 at its lower end adapted to engage the cross-member 12 when the box is in its normal position, so as to 85 hold said box in such position. The upper end of the latch 19 projects above the pivot 20 and is beveled, as shown at 22 in Fig. 3, so as not to interfere with swinging the lower end of the latch out from under the 90 cross-member 12. Normally the latch 19 is held in engagement with the cross-member 12 by gravity, as shown in Fig. 3.

95 23 indicates an end-gate, which is pivoted at its upper end upon the cross-bar 10 and hangs pendent therefrom. Said end-gate is provided with curved sides 24, which are in alinement with the sides of the box and are adapted to fit closely against the curved ends thereof when the box is in its normal position, as shown in Figs. 1 and 2. At its lower 100 corners the end-gate is provided with locking-plates 25, the rear edges of which are beveled, as shown at 26 in Fig. 2, said beveled faces being adapted to be engaged by 105 pins 27 projecting laterally from the lower rear corners of the sides of the box, thus drawing the lower edge of the end-gate forward and locking the sides thereof tightly in contact with the sides of the box. It will be 110

apparent that when the box is in its normal position and is locked in such position by the latch 19, the end-gate will also be locked in operative position.

- 5 28 indicates handles carried at the ends of bars 29, which are pivoted at their front ends in line with or upon the axle 17 at the sides of the box and extend upward and rearwardly therefrom, as shown in Fig. 1.
- 10 This arrangement of the handle bars is such that said bars extend in a substantially radial line with respect to the axle; and when the bars are pivoted and adjustable, as hereinafter referred to, such relation is sustained 15 irrespective of the positions of adjustment of the bars. Said bars are held in position by locking-pins 30 which pass through perforations 31 in the vertical bars 9 of the side frames and through slots 32 in the bars 29.
- 20 Thus the height of the bars 29 and of the handles 28 may be adjusted as desired. 33 indicates a crossbar, which connects the rear ends of the bars 29 adjacent to the handles 28, as best shown in Figs. 1 and 4. By this 25 construction the operator may adjust the handles to the desired height and wheel the cart readily from place to place. In operation usually the operator may press against the crossbar 33 with his body while he pulls 30 on the handles 28, thus obtaining a better purchase in pushing the cart. When he desires to dump the load, he releases the latch 19 and raises the rear end of the bed, thereby 35 automatically releasing the end-gate which may swing forward away from the bed and provide a wide opening for the discharge of the load. When the cart is not in motion, it is supported by the standard 13. By pivoting the handle-bars in line with the 40 wheel-axes, the power of the operator in pushing or pulling the cart is applied to the best possible advantage, and the operator is enabled to handle the cart more easily.

Some of the improvements herein described may be applied to carts other than hand-carts, and the claims, therefore, should be construed accordingly.

That which I claim as my invention, and desire to secure by Letters Patent, is,—

- 50 1. In a cart, the combination of an axle and wheels, a frame comprising side frames mounted on said axle, and means connecting said side frames together, a bed pivotally mounted upon the axle between said side frames, an end-gate supported by said frame and coöperating with said bed when the latter is in operative position, and handle-bars connected with the axle and with the frame.
- 55 2. In a cart, the combination of an axle and wheels, a frame comprising side frames mounted on said axle, and means connecting said side frames together, a bed pivotally mounted upon the axle between said side frames, an end-gate supported by said frame and coöperating with said bed when the latter is in operative position, said end-gate having side extensions in alinement with 60 the sides of the bed, said extensions having inclined faces, the adjacent ends of the sides of the bed being also inclined and adapted to fit the inclined faces of said extensions whereby when the bed is in operative posi-

ter is in operative position, and bars pivoted in line with the axle and connected with the frame.

3. A hand-cart, comprising an inclosing frame, supporting wheels therefor, a tilting bed supported by the wheels, a swinging end-gate supported at its upper end by the frame and adapted to swing outward at its lower end away from the bed, said end-gate having sides coöperating with the sides of the bed to form a closed box, and handle-bars pivoted in line with the wheel axles and connected with the frame.

4. A hand-cart, comprising an inclosing frame, supporting wheels therefor, a tilting bed supported by the wheels, a swinging end-gate supported at its upper end by the frame and adapted to swing outward at its lower end away from the bed, said end-gate having sides coöperating with the sides of the bed to form a closed box, and handle-bars pivoted in line with the wheel axles and adjustably connected with the frame.

5. In a cart, the combination of an axle and wheels, a frame comprising side frames mounted on said axle, and means connecting said side frames together, a bed pivotally mounted upon the axle between said side frames, and an end-gate pivotally supported by said frame and coöperating with said bed when the latter is in operative position, said end-gate having side extensions adapted to aline with the sides of the bed and abut against the adjacent faces thereof to form a substantially closed box when the bed is 100 in operative position.

6. In a cart, the combination of an axle and wheels, a frame comprising side frames mounted on said axle, and means connecting said side frames together, a bed pivotally mounted upon the axle between said side frames, an end-gate pivotally supported by said frame and coöperating with said bed when the latter is in operative position, said end-gate having side extensions adapted to 110 aline with the sides of the bed and abut against the adjacent faces thereof to form a substantially closed box when the bed is in operative position, and means carried by the bed for holding the end-gate in operative position.

7. In a cart, the combination of an axle and wheels, a frame comprising side frames mounted on said axle, and means connecting said side frames together, a bed pivotally mounted upon the axle between said side frames, an end-gate supported by said frame and coöperating with said bed when the latter is in operative position, said end-gate having side extensions in alinement with 12 the sides of the bed, said extensions having inclined faces, the adjacent ends of the sides of the bed being also inclined and adapted to fit the inclined faces of said extensions whereby when the bed is in operative posi-

tion said extensions fit closely against and form continuations of the sides of the bed, and means for locking the end-gate to the bed when the latter is in operative position.

5 8. In a cart, the combination of an axle and wheels, a frame comprising side frames mounted on said axle, and means connecting said side frames together, a bed pivotally mounted upon the axle between said

10 side frames, an end-gate supported by said frame and coöperating with said bed when the latter is in operative position, said end-gate having side extensions in alinement with the sides of the bed, said extensions having inclined faces, the adjacent ends of the sides of the bed being also inclined and adapted to fit the inclined faces of said extensions whereby when the bed is in operative position said extensions fit closely

15 against and form continuations of the sides of the bed, pins projecting laterally from the lower corners of the sides of the bed adjacent to the end-gate, locking plates secured to the lower corners of the end-gate, said plates having beveled faces adapted to be engaged by said pins when the bed is

20

25

removed into operative position, and means for holding the bed in operative position.

9. A hand-cart, comprising a frame, supporting wheels therefor, a tilting bed supported by the wheels, an end-gate adapted to coöperate with the bed to close one end thereof, and handle-bars pivoted substantially in line with the wheel-axles and connected with the frame.

30 10. A hand-cart, comprising a frame, supporting wheels therefor, a tilting bed supported by the wheels, an end-gate adapted to coöperate with the bed to close one end thereof, and vertically-adjustable handle-bars pivoted substantially in line with the wheel-axles and connected with the frame.

40 11. A hand-cart, comprising a frame, supporting wheels therefor, a tilting bed supported by the wheels, and handle-bars pivoted substantially in line with the wheel-axles and connected with the frame.
